UNITED STATES PATENT OFFICE.

CHARLES DE QUILLFELDT, OF AMITYVILLE, NEW YORK.

BOTTLE-STOPPER.

SPECIFICATION forming part of Letters Patent No. 624,681, dated May 9, 1899.

Application filed September 1, 1898. Serial No. 689,990. (No model.)

To all whom it may concern:

Be it known that I, CHARLES DE QUILLFELDT, a citizen of the United States, residing at Amityville, in the county of Suffolk, 5 and State of New York, have invented certain new and useful Improvements in Bottle-Stoppers, of which the following is a specification.

This invention relates to improvements in bottle-stoppers of that class known as "lightning" stoppers, and by which the head of the stopper, which is supported on a U-shaped bail, is accurately and reliably centered in position by the closing of the stopper, so as 10 to produce the uniform closing of the bottle-mouth and even compression of the elastic gasket applied to the lower part of the stopper-head; and the invention consists of a bottle-stopper provided with an opening, a central raise on said stopper in said opening, and a bail in said opening, said bail having a bent portion formed at an angle greater than the angle between the sides of the raise and bearing by its bent portion on said raise when 15 the stopper is applied to the bottle.

In the accompanying drawings, Figure 1 represents a side elevation of my improved bottle-stopper, showing the same applied to a bottle. Fig. 2 is a rear elevation of the 20 same. Fig. 3 is a vertical transverse section through the head of the stopper on line 3 3, Fig. 2, drawn on a larger scale; and Fig. 4 is a vertical transverse section through the head on line 4 4, Fig. 1.

Similar letters of reference indicate corresponding parts.

Referring to the drawings, A represents the bottle-neck, and B the closing-lever, which is applied in the usual manner by means of 40 a neck-wire a to the neck of the bottle, and which is provided with eyes for engaging the inwardly-bent lower ends of the bail C, which passes through a transverse opening in the head D of the stopper. The stopper D is made 45 of porcelain or other suitable material and provided with a transverse opening d, through which the bail C can readily pass for assembling the parts of the stopper when applying it to the bottle-neck. The transverse open-

ing d is not of equal size throughout, but is 50 contracted at its central portion by providing the lower interior portion of the head with a raise formed by inclines extending from the lower edge of the opening toward the center of the opening, as shown clearly in Figs. 2 55 and 4. The top and bottom of the opening thus diverge from each other from the central raise toward the mouth of the opening, thereby permitting considerable movement of the stopper on the bail. This interior raised portion e thus formed in the transverse opening of the stopper-head serves in connection with the centrally-bent portion f of the bail C for the purpose of producing the accurate and reliable centering of the stopper when the 60 same is pressed by the closing-bail C into the mouth of the bottle, so that the rubber gasket g, which is applied to the lower part of the stopper, is compressed in an even and uniform manner, whereby the uniform and tight 70 closing of the stopper in the mouth of the bottle is obtained.

The interior raise in the opening of the stopper-head does not prevent the free motion of the head on the bail, which is an essential point in bottle-stoppers of this class; but it secures the connection with the central bend in the transverse portion of the bail, and thereby the automatic and reliable centering of the stopper-head when the bail is 80 closed. This is an important feature, as the uneven compression of the gasket or irregular position of the stopper-head in closing the bottle is entirely obviated and a tight and reliable and uniform closing of the bottle by 85 the stopper obtained.

To avoid any chance of failure of the stopper to properly conform to the bottle-mouth and perfectly seat itself thereon, the angle between the sides of the raise may be less than 90° the angle between the sides of the bail, as in Figs. 3 and 4, and the central raise may be rounded and the bail curved instead of sharply bent.

Having thus described my invention, I 95 claim as new and desire to secure by Letters Patent—

The combination of a stopper provided

with an opening, a central raise on said stopper in said opening, and a bail in said opening, said bail having a bent portion formed at an angle greater than the angle between
5 the sides of the raise and bearing by its bent portion on said raise when the stopper is applied to the bottle, substantially as set forth.

In testimony that I claim the foregoing as my invention I have signed my name in presence of two subscribing witnesses.

CHARLES DE QUILLFELDT.
